(57) **CLAIM**

The ornamental design for a shoe insert, as shown and described.

DESCRIPTION

FIG. 1 is a perspective view of a shoe insert showing my new design;

FIG. 2 is a top plan view thereof;

FIG. 3 is a bottom view thereof;

FIG. 4 is a right side elevational view thereof;

FIG. 5 is a left side elevational view thereof;

FIG. 6 is a rear end view thereof;

FIG. 7 is a front end view thereof;

FIG. 8 is a perspective view of an alternative embodiment of my new design;

FIG. 9 is a top plan view of the alternative embodiment;

FIG. 10 is a bottom view of the alternative embodiment;

FIG. 11 is a right side elevational view of the alternative embodiment;

FIG. 12 is a left side elevational view of the alternative embodiment;

FIG. 13 is a front end view of the alternative embodiment; and,

FIG. 14 is a bottom view of the alternative embodiment.
